UNITED STATES PATENT OFFICE.

LEO MILLER CHAPMAN AND JAMES MADISON GELATT, OF LOUISVILLE,
KENTUCKY.

DESIGN FOR A NUT-LOCK WASHER.

SPECIFICATION forming part of Design No. 30,955, dated June 6, 1899.

Application filed April 17, 1899. Serial No. 713,412. Term of patent 31 years.

To all whom it may concern:

Be it known that we, LEO MILLER CHAPMAN and JAMES MADISON GELATT, citizens of the United States, residing at Louisville, in the county of Jefferson and State of Kentucky, have invented and produced a new and original Design for a Nut-Lock Washer, of which the following is a specification, reference being had to the accompanying drawings, forming a part thereof, in which—

Figure 1 is a view of one side of our newly-designed nut-lock washer; Fig. 2, a similar view of the opposite side, and Fig. 3 a section on the line 3 3 of Fig. 2.

As shown in the drawings, our newly-designed nut-lock washer consists of a circular disk A, one side of which is provided with a circular raised portion B, whereby the central portion of the washer is made thicker than the outer portion thereof and whereby an annular flange or rim portion C is formed, which is provided with a plurality of tangen-

tial slits or slots D. The tangential slots or slits D open outwardly, and the inner ends thereof terminate adjacent to the perimeter 25 of the central raised portion B. The central portion of the washer is also provided with a circular opening E, at one side of which is an inwardly-directed lug or projection F.

Having fully described our invention, we 30 claim as new and desire to secure by Letters Patent—

The design for a nut-lock washer herein shown and described.

In testimony that we claim the foregoing as 35 our invention we have signed our names, in presence of the subscribing witnesses, this 13th day of April, 1899.

LEO MILLER CHAPMAN.
JAMES MADISON GELATT.
